UNITED STATES PATENT OFFICE.

CYRUS COPLANTZ, OF JOLIET, ILLINOIS, ASSIGNOR OF ONE-HALF TO
A. S. CHEESEMAN, OF JOLIET, ILLINOIS.

LADDER.

No. 823,512.

Specification of Letters Patent.

Patented June 19, 1906.

Application filed June 5, 1905. Serial No. 263,682.

To all whom it may concern:

Be it known that I, CYRUS COPLANTZ, a citizen of the United States, residing at Joliet, in the county of Will and State of Illinois, have invented certain new and useful Improvements in Ladders, of which the following is a specification.

My invention is concerned with a novel extensible ladder having sliding sections and adapted especially for firemen's use, and is designed to produce a ladder of the class described that shall be capable of rapid extension to the required height and which shall be so constructed as to maintain the necessary rigidity and strength in all degrees of extension.

To illustrate my invention, I annex hereto two sheets of drawings, in which the same reference characters are used to designate identical parts in all the figures, of which—

Figure 1 is a side elevation of the ladder in its unextended and horizontal position as it rests upon the truck while it is being transported. Fig. 2 is a top plan view of the lower end of the ladder in the same position, but on a slightly-larger scale. Fig. 3 is a view similar to Fig. 1, but with the ladder extended and raised at an angle, which, however, is much less than that at which it is ordinarily extended, it being illustrated in this angle to accommodate it to the dimensions of the sheet of drawings. Fig. 4 is an enlarged sectional view on the line A A of Fig. 3. Fig. 5 is a similar view on the line B B of Fig. 3. Fig. 6 is an enlarged view in section on the line C C of Fig. 2.

Where my invention is used as a firemen's ladder which is to be transported rapidly from place to place, I mount it upon a horizontal base 10, which may be of any desired construction and which will be provided with the customary wheels and running-gear, so as to make a complete truck thereof. In order to secure an ample base in all directions in case it becomes necessary to raise the ladder at an angle to the plane parallel to the length of the base or truck, I provide it with a plurality of (preferably four) arms 11, which are pivoted at the sides of the base 10 in the bearings 12, so that they can be folded alongside the base, as shown in Fig. 2, while the apparatus is being transported or so that they can be extended at right angles thereto, as shown in dotted lines in Fig. 2, when it is desired to extend the base as suggested. In order to support the outer ends of these arms

11 from the ground irrespective of the irregularities thereof, I provide them at their outer ends with adjustable legs, which may be of any desired form, but which I preferably construct of the slotted ratchet-bars 13, which are supported from and operated by the levers 14, which carry the spring-held links or dogs 15, which, coöperating with the teeth of the ratchet-bars, enable the outer ends of the arms to be jacked up to any extent that may be necessary in order to give a firm support to the truck-base. As shown in Fig. 2, these lifting-jacks and their operating-levers are placed on alternate sides of the ends of the bars, and the truck-base is recessed, as at 15, in order to enable the arms 11 to be folded in the position shown without interference.

The ladder proper is mounted upon a turn-table 16, which preferably consists of a metallic disk, which is mounted to rotate about the bearing-post 17 as a center. In order that this table may rotate easily, I preferably mount it upon a plurality of antifriction-rollers 18, (best seen in Figs. 1 to 3,) which are journaled in suitable bearings on the truck-base 10, so as to support the turn-table thereon and permit its free rotation.

Projecting upward from the turn-table are the pair of standards 19, which are connected by the generally-U-shaped piece 20, which has its ends secured upon the horizontal upper portions of the standards 19. At the center of the U-shaped portion is a cross-piece 21, the U-shaped piece being supported beneath the cross-piece by the sleeve 22, surrounding the vertical bearing shaft or rod 17 and having its lower end resting upon the table 16, being preferably screwed into the nut 23, secured to the center of the table. The cross-piece 21 has its outer ends turned down to form pintles for the bearings 24, which are secured in the lower ends of the side pieces 25 of the lowermost ladder-section. The angle at which this lowermost section, which may be said to be relatively stationary to the other sliding sections supported thereby, is held is controlled by the segmental rack-bars 26, secured to the outer sides of the side pieces and meshing with the gear-pinions 27, which are journaled on pintles 28, supported upon the upper sides of the U-shaped piece 20. The gear-pinions 27 might be provided directly with operating-crank; but in order to enable the angle to be changed with less power and to hold it in any position to which

it may be set by the inertia of the mechanism I preferably secure to the gear-pinion 27 a gear-wheel 29, which is driven by the gear-pinnions 30, one of which is secured to each 5 end of a shaft 31, journaled in suitable bearings formed adjacent to the bearings for the pintles 28. A crank-handle 32 may be provided for one or both ends of this shaft, as may be found necessary, and by turning this 10 shaft it will be seen that the lowermost section, which, as seen in Fig. 1, normally rests in a substantially horizontal position upon the cross-piece 33 of the support 34, may be swung upward to any desired position, it 15 preferably approximating a vertical position when the ladder is in use.

While I do not limit myself to any precise number of sections, I preferably employ three sections, of which the lowermost one is, 20 as I have said, relatively stationary, while the intermediate section 35 is slideable on the lower section and has the under surfaces of its side pieces resting directly upon and sliding over the upper surfaces of the side pieces 25 of the lowermost section. The third section 36 is also slideable, but is preferably narrower, so that its side pieces are within and above the side pieces of the intermediate section and are supported in the manner to be described. 30

The bottom section has provided at its upper ends the U-shaped bearing-pieces 37, secured thereto, in which are mounted the anti-friction-rollers 38, upon which the side pieces 35 of the intermediate section 35 slides. Secured to the outer sides of the side pieces 25, near their upper ends, are the yoke-shaped pieces 39, which have journaled therein the antifriction-rollers 40 and 41 at the proper 40 height above the side pieces 25 so that the side pieces of the middle section 35 will be free to slide between the upper sides of the side pieces 25 and the rollers 40 and 41. The intermediate section 35 is constructed in a 45 somewhat similar manner at its upper end, it being provided with the two shafts or bearing-rods 42 and 43, which have journaled thereon immediately adjacent the side pieces the antifriction-rollers 44 and 45, respectively, 50 upon which the side pieces of the uppermost section 36 are adapted to slide. The side pieces 35 are provided with the yoke-shaped pieces 46, similar to the yoke-shaped pieces 39, which are provided with the antifriction-rollers 47 and 48, bearing upon the upper surfaces of the side pieces of the section 36, so 55 that said section will slide freely between the rollers 44 and 45 on its under side and the rollers 47 and 48 on its upper side. The section 35 is provided at its lower ends with the overhanging lugs 49, which prevent any side-wise movement of the intermediate section relative to the lower section upon which it slides. The section 36 is provided at its 60 lower ends with the downwardly-extending

lugs 49^a, which are set in flush with the outer edges of the section and coöperate with the inner edges of the section 35 to prevent any angular displacement.

To elevate the upper sections on the lower one, I provide the two pairs of winding-drums 50 and 51, both of which are preferably secured on the shaft 52, journaled in the bearings 53, secured upon the upper surfaces of the lower ends of the side pieces 25. A 70 ratchet-wheel 54 is also secured upon the shaft 52, and a dog 55 is suitably pivoted on one of the side pieces 25 so as to be in position to coöperate with the ratchet-wheel when desired and prevent the backward rotation of the shaft 52 and the possible premature descent of the sections. The intermediate section 35 is elevated by means of the pair of ropes 56, which are secured to the 75 lower end of the section 35, conveniently by being fastened to the lowermost rung of the ladder and extending up and over the sheaves 57, which are journaled on a bearing-rod 58 just inside of the side pieces 25 and thence down to the winding cylinders or drums 50, 80 to which the ends of the ropes are secured. As the shaft 52 is rotated it will be apparent that the winding up of the ropes 56 will elevate the intermediate section of the ladder.

The uppermost section 36 is elevated by 90 means of the pair of ropes 59, which are secured at 60 to the lower end of the section 36 and preferably by being secured to the lowermost rung of that section. These ropes extend upward over the sheaves 61, which are 95 preferably mounted on the shaft 43 just inside of the antifriction-rollers 45, and thence extend downward to the drums 51, to which they are secured. It will be apparent that 100 if the ends of the ropes 59 were secured to some stationary portion of the mechanism the upward movement of the middle section 35 would elevate the uppermost section at twice the rate of speed at which the middle section moves, and by attaching the ends of 105 the rope to the drums 51 I am enabled to move the uppermost section at a still greater rate of speed, since its rate of speed relative to the middle section will be represented by twice the diameter of the drums 50, plus 110 once the diameter of the drums 51, as against once the diameter of the drums 50 for the speed of the intermediate section. As I do 115 not desire to make the speed of the uppermost section four times that of the intermediate section, I reduce the diameter of the drums 51, as shown, to about half of the diameter of the drums 50, thus giving the uppermost section a speed of three times that 120 of the intermediate section.

While the mechanism thus far described has a certain degree of utility, I am enabled to increase it very materially by providing truss-ropes, so that the ladder-sections will be braced both from above and below. The 130

bracing from above is essential if the ladders are not supported at the top in order to prevent them from bending over from their own weight. The bracing from the under side is likewise essential where the ladder is extended and its top is allowed to rest against a wall, in which case the bracing overcomes the tendency to sag resulting from the weight of the sections. To secure this necessary bracing effect, I provide what may be called "rope-trusses," which consist of the truss-posts 62 and 63, secured to the outer sides of the upper ends of the sections 25 and 35, respectively. At both ends of all four of these truss-posts I provide the sheaves 64, which are journaled in the hook-shaped ends 65 of the truss-posts, so that the truss-ropes 66 and 67 will be held therein and guided thereby. These truss-ropes are secured at their upper ends to the top of the uppermost section, as at 68, and extend downward over the sheaves 64 and are attached at their lower ends to the winding-drums 69, which are rigidly secured on the shaft 70, journaled in the bearings 71, secured on the upper side of the lowermost side pieces 25. I may provide the shaft 70 with a squared end 72, as indicated, and operate it independently of the shaft 52 by a handle, as indicated in dotted lines at 73 in Fig. 2; but I preferably employ a gear-wheel 74, secured on the shaft 52, which meshes with a gear-wheel 75, loosely mounted upon the shaft 70, but adapted to be secured thereto by means of the clutch members 76, splined on the shaft 70 and adapted to be shifted into and out of engagement with the clutch member 77, formed on the hub of the gear-wheel 75. The ratio of the gear-wheels 74 and 75 and of the drums 50, 51, and 69 is such that as the ropes 56 and 59 are wound up, extending the sections, the truss-ropes 66 and 67 will be unwound, permitting their extension, while at the same time acting as truss-rods to brace the ladder-sections. When the ladder is to be lowered, the dog 55 is thrown out of engagement with the ratchet-wheel 54 and the dog 78, pivoted on the side piece 25, is thrown into engagement with the ratchet-wheel 80, secured on the shaft 70, and the shaft 52 is rotated in the opposite direction, which will have the effect of unwinding the ropes 56 and 59 and winding up the ropes 66 and 67, thus causing the descent of the ladder. By reason of the employment of the clutch members 76 and 77 I am enabled to operate the two sets of ropes independently, if desired, and if the truss-ropes should become somewhat loosened they can be tightened up by unclutching the shaft 70 and moving it independently of the shaft 52.

In order to strengthen the lowermost section, I may provide the steel truss-rod 81 and the truss-post 82 and suitably connect the rods at their ends in order to form an invert-

ed king-post truss, in the manner clearly shown.

While I have shown and described my invention as embodied in the form which I at present consider best adapted to carry out its purposes, it will be understood that it is capable of modifications and that I do not desire to be limited in the interpretation of the following claims, except as may be necessitated by the state of the prior art.

What I claim as new, and desire to secure by Letters Patent of the United States, is—

1. In a device of the class described, the combination with the base having the support at one end and the turn-table at the other end, of the bottom ladder-section pivotally mounted on said base and adapted to rest on the support when in a horizontal position, gearing for turning the lower section on its bearing to any desired extent, an intermediate section carried by and adapted to slide up on the bottom section, a top section carried by and adapted to slide up on the intermediate section, ropes connected to the bottom of each of the upper sections and running over sheaves on the tops of the adjacent lower sections, drums for winding up said ropes, and a single shaft driving all of said drums upon which all the ropes are wound to simultaneously slide both the upper sections up upon their supporting-sections.

2. In a device of the class described, the combination with the base having the support at one end and the turn-table at the other end, of the bottom ladder-section pivotally mounted on said base and adapted to rest on the support when in a longitudinal position, a circular rack on said section, a shaft parallel to the pivots of the section, reducing-gearing between the shaft and the rack whereby the lower section can be turned on its bearing to any desired extent, an intermediate section carried by and adapted to slide up on the bottom section, a top section carried by and adapted to slide up on the intermediate section, ropes connected to the bottom of each of the upper sections and running over sheaves on the tops of the adjacent lower sections, drums for winding up said ropes, and a single shaft driving all of said drums upon which all the ropes are wound to simultaneously slide both the upper sections up upon their supporting-sections.

3. In a device of the class described, the combination with the base having the support at one end and the turn-table at the other end, of the bottom ladder-section pivotally mounted on said base and adapted to rest on the support when in a horizontal position, gearing for turning the lower section on its bearing to any desired extent, an intermediate section carried by and adapted to slide up on the bottom section, a top section carried by and adapted to slide up on the intermediate section, truss-posts projecting from the tops

of the lower sections, lifting-ropes connected to the bottom of each of the upper sections and running over sheaves on the tops of the adjacent lower sections, truss-ropes secured 5 to the tops of the top sections and running over the truss-posts, drums for winding up all of said ropes, and a single shaft driving said drums, by which all the ropes are wound simultaneously to slide both of the upper sections up upon their supporting-sections and 10 at the same time pay out the truss-ropes.

4. In a device of the class described, the combination with the base having the support at one end and the turn-table at the other 15 end, of the bottom ladder-section pivotally mounted on said base and adapted to rest on the support when in a horizontal position, gearing for turning the lower section on its bearing to any desired extent, an intermediate section carried by and adapted to slide up on the bottom section, a top section carried by and adapted to slide up on the intermediate section, truss-posts projecting from the tops of the lower sections, guiding-sheaves on 20 the truss-posts, lifting-ropes connected to the bottom of each of the upper sections and running over sheaves on the tops of the adjacent lower sections, truss-ropes secured to the tops of the top sections and running over the 25 sheaves on the truss-posts, drums for winding up all of said ropes, and a single shaft driving said drums, by which all the ropes are wound simultaneously to slide both of the upper sections up upon their supporting-sections and 30 at the same time pay out the truss-ropes.

5. In a device of the class described, the combination with the lower ladder-section, of the intermediate section adapted to slide on 40 the lower section, the upper section adapted to slide on the intermediate section, a winding-drum associated with the lower section, a pair of ropes adapted to be wound thereon and secured to the bottom of the intermediate 45 section, sheaves at the top of the lower section over which the ropes run, a second pair of ropes secured to the bottom of the uppermost section and to the winding-drum, a pair of sheaves at the top of the intermediate section 50 over which the second pair of ropes run, the truss-posts carried at the tops of the lower and intermediate sections, sheaves carried by said truss-posts, the truss-ropes secured to the top of the uppermost section and extending 55 down over the sheaves on the truss-posts, drums on which the truss-ropes are wound, and gearing between the winding-drums to rotate them in the proper direction and at the proper rates to alternately pay out and wind 60 up said ropes.

6. In a device of the class described, the combination with the lower section, of the intermediate section adapted to slide thereon, the uppermost section adapted to slide on 65 the intermediate section, the winding-drum

journaled adjacent the lower end of the lower section, the lifting-ropes for the intermediate section secured at one end to the winding-drum and at the other end to the lower end of the intermediate section, the sheaves at the top of the lower section over which said ropes run, the winding-ropes for the uppermost section secured at one end to the winding-drum and at the other end to the bottom of the uppermost section, the sheaves at the top 70 of the intermediate section over which the winding-ropes for the uppermost section run, the truss-posts carried at the tops of the lowermost and of the intermediate sections, the sheaves carried at the ends of said truss-posts, 75 the truss-ropes secured at the top end of the uppermost section and extending down over the sheaves on the truss-posts, the winding-drum to which the truss-ropes are secured, and gearing between the two drums to rotate 80 them in the opposite directions and in the proper sequence, substantially as described.

7. In a device of the class described, the combination with the lower section, of the intermediate section adapted to slide thereon, 90 the uppermost section adapted to slide on the intermediate section, the winding-drum journaled adjacent the lower end of the lower section and having two sections of different diameters, the lifting-ropes for the intermediate section secured at one end to the larger portion of the winding-drum and at the other end to the lower end of the intermediate section, the sheaves at the top of the lower section over which said ropes run, the winding-ropes for the uppermost section secured at 95 one end to the smaller portion of the winding-drum and at the other end to the bottom of the uppermost section, the sheaves at the top of the intermediate section over which the winding-ropes for the uppermost section run, the truss-posts carried at the tops of the lowermost and of the intermediate sections, the sheaves carried at the ends of said truss-posts, the truss-ropes secured at the top end 100 of the uppermost section and extending down over the sheaves on the truss-posts, the winding-drum to which the truss-ropes are secured, and gearing between the two drums to rotate 105 them in the opposite directions and in the proper sequence, substantially as described.

8. In a device of the class described, the combination with the lower section, of the intermediate section adapted to slide thereon, 110 the uppermost section adapted to slide on the intermediate section, the winding-drum journaled adjacent the lower end of the lower section, the lifting-ropes for the intermediate section secured at one end to the winding-drum and at the other end to the lower end of the intermediate section, the sheaves at the top of the lower section over which said ropes run, the winding-ropes for the uppermost section secured at one end to the wind- 115

ing-drum and at the other end to the bottom of the uppermost section, the sheaves at the top of the intermediate section over which the winding-ropes for the uppermost section run, the truss-posts carried at the tops of the lowermost and intermediate sections, the sheaves carried at the ends of said truss-posts, the truss-ropes secured at the top end of the uppermost section, and extending down over the sheaves on the truss-posts, the winding-drum to which the truss-ropes are secured, a large gear on the lifting-rope drum, and a small gear on the truss-rope drum with which said large gear meshes, substantially as and for the purpose described.

9. In a device of the class described, the combination with the lower section, of the intermediate section adapted to slide thereon, the uppermost section adapted to slide on the intermediate section, the winding-drum journaled adjacent the lower end of the lower section, the lifting-ropes for the intermediate section secured at one end to the winding-drum and at the other end to the lower end of the intermediate section, the sheaves at the top of the lower section over which said ropes run, the winding-ropes for the uppermost section secured at one end to the winding-drum and at the other end to the bottom of the uppermost section, the sheaves at the top of the intermediate section over which the winding-ropes for the uppermost section run, the truss-posts carried at the tops of the lowermost and intermediate sections, the sheaves carried at the ends of said truss-posts, the truss-ropes secured at the top end of the uppermost section and extending down over the sheaves on the truss-posts, the winding-drum to which the truss-ropes are secured, a large gear on the lifting-rope drum, a small gear on the truss-rope drum with which said large gear meshes, and a clutch between the gears and the truss-rope-drum shaft so that the truss-rope-drum shaft can be tightened or loosened as desired, substantially as and for the purpose described.

10. In a device of the class described, the combination with a truck-base, of the extensible ladder mechanism thereon, the turntable upon which it is mounted, the laterally-extensible horizontal bars pivoted to the sides of the base, and the adjustable legs carried by the ends of the bars, consisting of the vertical ratchet-bars, the levers pivoted to the ends of the horizontal bars, and the dogs carried by the levers cooperating with the ratchet-teeth, substantially as described.

11. In a device of the class described, the combination with the relatively stationary section carrying the antifriction-rollers at the top, and the yoke-shaped members carrying the antifriction-rollers on its upper side near the top, of the intermediate section adapted to slide between the rollers on the lower section, and carrying the antifriction-

rollers near its upper end and the yoke-shaped members carrying antifriction-rollers on the upper side near the top of the intermediate section, the top section adapted to slide between the antifriction-rollers on the intermediate section, and means for extending and withdrawing the upper sections.

12. In a device of the class described, the combination with the relatively stationary section carrying the antifriction-rollers at the top, and the yoke-shaped members carrying the antifriction-rollers on its upper side near the top, of the intermediate section adapted to slide between the rollers on the lower section, and carrying the antifriction-rollers near its upper end and the yoke-shaped members carrying antifriction-rollers on the upper side near the top of the intermediate section, the top section adapted to slide between the antifriction-rollers on the intermediate section, the truss-posts having the sheaves at their ends carried at the upper ends of the lower and intermediate sections, the truss-ropes secured to the upper end of the top section and extending down over the sheaves, and means for extending and withdrawing the upper sections and at the same time keeping the truss-ropes taut.

13. In a device of the class described, the combination with the relatively stationary section carrying the antifriction-rollers at the top, and the yoke-shaped members carrying the antifriction-rollers on its upper side near the top, of the intermediate section adapted to slide between the rollers on the lower section, and carrying the antifriction-rollers near its upper end and the yoke-shaped members carrying antifriction-rollers on the upper side near the top of the intermediate section, the top section adapted to slide between the antifriction-rollers on the intermediate section, the truss-posts having the sheaves at their ends carried at the upper ends of the lower and intermediate sections, the truss-ropes secured to the upper end of the top section and extending down over the sheaves, a winding-drum journaled adjacent the bottom of the lower section, ropes adapted to be wound thereon and passing over sheaves carried at the top of the lowermost and intermediate sections and adapted to be secured to the bottoms of the uppermost and intermediate sections, respectively, another winding-drum for the truss-ropes, and means for rotating said drums.

14. In a device of the class described, the combination with the relatively stationary section carrying the antifriction-rollers at the top, and the yoke-shaped members carrying the antifriction-rollers on its upper side near the top, of the intermediate section adapted to slide between the rollers on the lower section, and carrying the antifriction-rollers near its upper end and the yoke-shaped members carrying antifriction-rollers on the up-

per side near the top of the intermediate section, the top section adapted to slide between the antifriction-rollers on the intermediate section, the truss-posts having the sheaves at their ends carried at the upper ends of the lower and intermediate sections, the truss-ropes secured to the upper end of the top section and extending down over the sheaves, a winding-drum journaled adjacent the bottom of the lower section, ropes adapted to be wound thereon and passing over sheaves carried at the top of the lowermost and intermediate sections and adapted to be secured to the bottoms of the uppermost and inter-

mediate sections, respectively, another winding-drum for the truss-ropes, and gearing between said drums adapted to rotate them in the opposite direction and at the proper speed so that as the lifting-ropes are wound up the truss-ropes are extended, and vice versa.

In witness whereof I have hereunto set my hand this 1st day of June, 1905.

CYRUS COPLANTZ.
